ATTORNEY

UNITED STATES PATENT OFFICE.

ALBERT A. MCINTYRE, OF BONNERS FERRY, IDAHO.

METHOD OF MAKING A DIE.

1,398,196.

Specification of Letters Patent. Patented Nov. 22, 1921.

Application filed April 29, 1919, Serial No. 293,527. Renewed October 11, 1921. Serial No. 507,158.

To all whom it may concern:

Be it known that I, ALBERT A. MCINTYRE, a citizen of the United States, residing at Bonners Ferry, in the county of Boundary 5 and State of Idaho, have invented new and useful Improvements in Methods of Making a Die, of which the following is a specification.

The object of this invention is to provide 10 a device for the synthetic and analytic study of a complete entity by segregation and combination of the parts of such entity.

In the more specific form of my invention the same is applied to the study of geography, and will be so illustrated, the device 15 presenting, when united, an integral or complete political entity which is sub-divided so that it can be segregated into predetermined and definite integers.

More specifically speaking, my invention 20 has to do with an improved method whereby a previously printed and completed map, for instance, may be subsequently severed or sub-divided into its various counties, if the 25 map is of a State, or into its component States, if the map is of a country. In this connection, sub-divided maps have heretofore been made at great expense owing to the necessity for individual hand work in 30 their production, as regards the severance of the entity into its integers.

In accordance with my improved method, 35 an imprint of the exact configuration of the map or entity is made upon a block of which an improved die is afterward made. This block is sub-divided on the exact lines 40 of the configuration impressed thereon, and in the kerfs of the saw or other sub-dividing tool are disposed cutting ruling means. The cutting ruling means project in relief from 45 that face of the block or die which presents the configuration in the negative form. Therefore, when this cutting die is brought into sub-dividing impression engagement 50 with the previously printed map, in positive facing relation toward the die, the die will sever the map into its component integers precisely on the lines of configuration division of the map. Thus, by a mechanical 55 and rapid method I am enabled to very rapidly and accurately produce sub-divided entities which heretofore have been altogether too costly to in any way figure as a large and cheap volume product.

As a mechanism, my invention comprises 55 a cutting die having impressed on one face

thereof the configuration of the finished printed matter to be sub-divided, the die being severed on the lines of the configuration and having cutting ruling means interposed in the kerfs of the saw or other severing implement.

My invention has other features and objects which will be more fully described in connection with the accompanying drawings and which will be more particularly pointed out in and by the appended claims.

In the drawings:

Figure 1 is a face view of an engraved plate, in negative, on which the configuration of the map appears, it being assumed that this plate is on the bed of a platen press.

Fig. 2 is a contracted view of a tympan on which the initial printed impression from 75 the plate may be assumed to have been made, or about to be made, such impression being in the positive.

Fig. 3 is a wood or other block on the face of which an offset impression has been made, 80 or on which a direct impression might have been made from the plate itself, this view being taken before the block is sub-divided.

Fig. 4 is an edge view of the plate shown 85 in Fig. 1.

Fig. 5 is a face view of the block after it has been sub-divided and equipped with its cutting rule means and clamped in a chase.

Fig. 6 is a sectional view on line 6-6 of Fig. 5.

Fig. 7 is a face view of the sub-divided product.

Fig. 8 is an edge view thereof.

Like characters of reference designate similar parts throughout the different figures of 95 the drawings.

My improved method may be carried out in at least two different ways. The engraved plate 1, having on its face the configuration of the map to be printed, as indicated at 2, may be secured to the bed of a platen press. A tympan 3, on the platen, may serve to take an inked impression from the plate 1. Preferably, two or three impressions will be made on the tympan not 105 only for the purpose of getting a clear and continuous line impression but also for the purpose of getting enough ink on the tympan to make an unbroken offset impression therefrom. The plate is then removed from the 110 bed and an integral wood or like block 4 is mounted on the bed. An offset impression

is then transferred from the tympan to the wood block 4, as indicated by the lines in Fig. 3. Now it will be seen that the negative impression from the plate 1 will have 5 been transferred to the tympan, in positive form, and the offset impression will have been transferred back to the block in negative form. The block 4 is then severed on lines 2 thereby sub-dividing the same into 10 counties indicated by lines 2. Instead of giving the counties names, I will represent them by letters. "a", "b", "c", "d", "e", "f", "g".

The hack-saw or other implement used to 15 sub-divide the block 4 will leave a kerf or kerfs, as clearly indicated at 5, in the finished product, these kerf faces being unnecessary to illustrate in Fig. 4. I interpose in these kerfs ruling elements 6, similar elements 7 bordering the edges of the block. These ruling elements or strips may either be bent initially to fit the configuration of the kerfs, or, when the sub-divided block is clamped in the chase 6, the elements may be 20 shaped to form. However, in any event, the ruling elements or members are necessarily made of thin metal which can readily be shaped to the necessary form and I do not wish to be limited to any specific manner of so doing although I consider it a novel 25 feature to shape these ruling elements, broadly. These ruling elements are preferably of a width slightly in excess of the thickness of the block so that their edges 8 will project in relief from one face of the block. These projecting edges are sharpened 30 to form knife or cutting edges as will be clearly seen by reference to Fig. 6. Now it will be clear that as far as the block is concerned it does not make any difference on 35 which face thereof the printed impression is made. In any event, when the block is in use for sub-dividing previously printed maps, in positive, that face of the block 45 which will be considered face 9 will be presented to the entity to be sub-divided, and face 9 will present the configuration in negative form. Therefore while the ink impression or transfer might have been made 50 on face 10 of the block, it will be a simple matter to dispose the ruling elements so that their cutting edges will project in relief from the opposite face.

If desired, a direct impression from plate 55 1 may be made on the block, in the first instance, by fixing the block on the platen of the press. Either way, is clearly within the purview of my invention.

Taking a simple method of describing the 60 operation, it will be assumed that the plate 1 is disposed on the bed of a platen press and that a number of the desired quantity of cards 11 have been printed with the map as engraved on the plate. Thus it will be 65 assumed that one thousand map cards 11

have been completely printed and that these cards are integral and undivided cards. Either before or after this printing operation, my improved die will have been made up and clamped into a chase, as shown in Fig. 5. After the cards have dried, then the plate 1 is taken out of the press and the structure shown in Fig. 5 is substituted therefor on the bed. These printed cards are then taken one by one, in the usual manner, and fed into place on the gages of the platen. As the press operates, the cutting ruling edges of the die will be brought into impression engagement with the printed cards and will subdivide them as indicated at 5. The cutting edges of the ruling elements will necessarily register accurately with the lines on the previously printed map by reason of the fact that the guiding lines of severance for subdividing the block constituted the impression from the very plate which printed the maps. Now if the cards 11 were completely subdivided, considerable difficulty would be encountered in removing the integers from the platen. Therefore, 80 certain of the cutting edges of the rule elements are interrupted, as indicated at 12, in Fig. 6. By this means, the integers of the map will be completely severed except for those minute junctures formed or left by the slight interruptions 12. Thus the substantially completely subdivided integers can be bodily removed from the platen with the same facility as the integral card was inserted thereon. 90

In some instances, the card when being printed will be slightly larger, relatively speaking, than that shown in Fig. 3, in which event the bordering cutting rules 7 would cut the edges of the card to size. 100

By means of the device and method invention herein disclosed I have proven that integers of a complete entity may be segregated by physical subdivision in such an economical and cheap manner as to be readily accessible to the general public at a very low figure. 105

When the device of my invention is applied to the making of maps, the resulting product offers facility for the synthetic and analytic study of geography, not only as regards the general shape but also the location of political entities such as counties or States, and by this means, either the young or adult student obtains visual and mental impressions of a not only graphic but lasting nature in the putting together and taking apart of the subdivided integers. 115

It is believed that the novelty and utility of my invention will be fully understood from the foregoing description, and while I have herein shown and described different species of the genus, I do not wish to be limited thereto except for such limitations as the claims may import. 125

I claim—

1. The herein-described method of making a die for the subdivision of integers of an entity, which consists, in making on a die stock or block an impression from the engraved or other printing plate in exact facsimile of the configuration of the entity and its integers to be printed, in subdividing the block on the lines of such configuration, and 10 in interposing cutting rules in such lines of division of the block with the cutting edges of said rules in relief from the cutting or impression side of the block.

2. The herein-described method of making a die for subdividing the integers of an entity, which consists, in transferring upon a die block a line impression of such entity, in subdividing the block into integers on the lines of such impression, in interposing cutting rules in the lines of such subdivision, 15 and in applying pressure to the divided block integers to shape the rules to said lines of division.

In testimony that I claim the foregoing as my own, I hereby affix my signature.

ALBERT A. MCINTYRE.
